UNITED STATES PATENT OFFICE.

LAWRENCE R. JONES, OF PEORIA, ILLINOIS.

VALVE-LOCK.

1,395,678.

Specification of Letters Patent.

Patented Nov. 1, 1921.

Application filed August 14, 1919. Serial No. 317,404.

To all whom it may concern:

Be it known that I, LAWRENCE R. JONES, a citizen of the United States, residing at Peoria, in the county of Peoria and State of Illinois, have invented certain new and useful Improvements in Valve-Locks, of which the following is a specification.

The invention relates to valve locks and has especial reference to improved means for locking a valve with its port open or closed.

One of the objects of the invention is to provide in a valve lock a handle, in coöperation with other parts of a valve structure, whereby the valve may operatively be

15 moved to open and close the valve port, and which is made in two major parts hinged together. The extended free end of the handle, by which the valve is moved, is adapted to be folded back over and above

20 the part of the handle that is directly attached to the valve stem and is adapted to be locked in folded position only when the valve occupies a predetermined position with reference to its port. At the time the

25 handle is locked in folded position, it moves parts that will positively maintain the valve in the position in which it has been placed by the handle, and the arrangement is such that the handle may be locked in folded

30 position only when the valve has been moved to a predetermined extent, that is to say, to open position or to closed position, as the case may be, it not being possible to fold the handle and lock the valve at any intermediate position.

Furthermore the arrangement is such that the valve handle cannot be removed from the valve stem when the valve is locked, because the extended end of the handle is folded over and guards the means by which the handle is held to the stem.

The normal position of the valve handle is in its folded position, and in this position it is to be locked, by use of a padlock or the like. The valve-operating part may be constructed so that the valve may be positively locked, by manipulation of the handle, when the valve is either entirely open or completely closed, but not in any intermediate position, or it may be conveniently arranged so that the valve may be locked only when it is open, by constructing the valve structure especially for this purpose, or alternatively, by constructing it so that

50 it may be locked only when it is closed.

55 In the drawings, I have shown a valve

substantially the same as that disclosed in my copending application Serial No. 281,028 filed March 6, 1919, in which the claims are directed to improvements in the valve 60 structure.

Other and further objects of my invention will become readily apparent, to persons skilled in the art, from a consideration of the following description when taken in conjunction with the drawings, wherein:

Figure 1 shows a plan view of a valve with my handle attached thereto and in extended position adapted to rotate the valve stem to close the valve.

Fig. 2 is a side elevation of the valve with the handle in folded position, ready to be locked, showing it in extended position in dotted lines.

Fig. 3 is a transverse section through the 75 valve, taken on line 3—3 of Fig. 1.

Fig. 4 is a transverse section of the valve casing showing the valve port open.

Fig. 5 is a central section through the valve stem and the handle, showing the 80 parts in folded position.

Fig. 6 shows the parts in section in extended position.

Fig. 7 is a section taken on line 7—7 of Fig. 5.

In all the views the same reference characters are employed to indicate similar parts.

10 is a casing, substantially the same as that disclosed in my prior application to which attention has heretofore been called. 90 11 is the valve stem, rotatable to move the valve disk 12 so that the port 13 will register with the port 14 of the valve casing 10 to open the valve port. Secured to the valve stem is a bifurcated arm 15, having between 95 its two prongs a stud 16 that projects upwardly from the valve plate 12. When the stem is rotated the arm 15 will be moved to the dotted line position, shown in Fig. 4, whereupon the port 13 will be in register 100 with the openings 14 through the valve casing.

My invention has especial reference to the valve operating handle in which a part 17 is connected to the valve stem 11 by a washer 18 and a screw 19. The upper portion of the valve stem is rectangular in section, which fits in a rectangular opening in the part 17 of the handle. The outer end of the handle 17 is bifurcated into two prongs 20 and 21, 110 between which the outwardly extended portion 22 is pivoted, by the bolt 23 passing

through the inner end 24, of the part 22, and through the prongs 20 and 21 of the part 17. The part 22, of the handle, is provided with a slot 25 which overlies the staple 26 that rises from the part 17 and which contains an opening or perforation 27, within which to insert a padlock, or the like, so that the part 22 cannot be straightened out into dotted line position shown in Fig. 2 to operate the valve unless the lock has been removed from the slot 27. The part 22, of the handle, is provided with a nose 28 which is insertible in the interdental space 29 between the teeth 30 and 31 of the dog 32. The dog 32 is pivoted on a bolt 33 that passes through flanges 34 depending from the part 17 of the handle. The lower end 34 of the dog 32 bears against a hub 36 that surrounds the stem 11. The hub is inclined, as at 37, and the end 34, of the dog, bears against this part 37, when the valve is not in open or closed position, so that the projection 38 bearing upon the upper surface of the dog 32, when the part 34 is against the inclined surface of the hub, thus preventing the handle part 22 from being moved into horizontal position to be locked above the part 17. The end of the hub 36 provides a shoulder 39, and when the end 34 of the dog 32 is opposite the shoulder 39, then the part 38 will press upon the upper part of the dog 32 and move the projection 34 behind the shoulder, whereupon the handle 22 may be moved to horizontal position and the lock inserted in the staple 26, as clearly shown in Fig. 5. Now if a shoulder 39 is provided only on one side of the hub 36, clearly, the handle part 22 may not be depressed into locking position because the projection 34 of the dog will be in contact with the inclined wall 37 of the hub 36, preventing the part 22 of the handle from being moved to locking position. If desired, however, another shoulder in the hub 36 may be provided substantially on line 40, as shown in Fig. 1, whereupon the handle may then be locked when the valve has been moved to the position that it would occupy when the projection 34 of the dog is behind the shoulder indicated by the dotted line 40 or when the valve is closed. The shoulder, indicated by the dotted line 40, which may or may not be used, may be employed in addition to the shoulder 39, or it may be used instead of the shoulder 39, according to the exigencies presented by the case.

Now it will be manifest that when the handle part 22 is in locked position, the dog 32 is thereby forced behind the shoulder 39, and therefore the handle cannot be rotated and the valve stem 11 must remain stationary to hold the valve in whatever position it may be in.

After the valve has been locked, as shown in Fig. 5, and it is desired to unlock it, or

close it, as the case may be, the padlock is removed from the orifice 27, of the staple 26, and the valve handle part 22 is rotated on the pivot 23, whereupon the nose 28 of the handle will enter the space 29, between the teeth 30 and 31 of the dog, and lift the dog so that the lower projection 34 will be raised out from behind the shoulder 39, formed on the hub 36, whereupon the valve may be rotated, but, in the particular embodiment exemplified, it may not be again locked in the position shown in Fig. 5 until it has been returned, so that the dog 32 may again enter the space behind the shoulder 39, because the projection 38, of the handle part 22, bearing upon the upper surface of the dog 32 will not permit the part 22 to be entirely depressed until the projection 34 of the dog has been moved an extent shown in Fig. 5, wherein it is located behind the shoulder 39.

It will be noted that the handle part 22 overlies the screw 19, when the handle is in locked position, so that the screw 19 may not be removed and therefore the handle 90 cannot be taken from the valve stem 11 when the parts are locked together. Therefore there is no possibility of moving the valve to a new position so long as the parts are locked in the manner described. 95

While I have herein shown a single embodiment of my invention, for the purpose of clear disclosure, it will be manifest, to persons skilled in the art, that considerable variation in the configuration and disposition of the parts is permissible within the scope of the appended claims. 100

Having described my invention, what I claim is:—

1. A valve lock providing a valve stem; a handle providing two parts, an inner part removably secured to the said stem and an outer part hinged to the inner part and adapted to be folded over and to be locked to the inner part; an obstruction in the path of the handle when moved toward folded position, to prevent the parts from being locked together to hold the valve, except when the valve is in a pre-selected position, and means for securing the inner part of the handle to the stem rendered inaccessible by the overlying folding part. 110

2. A valve lock having in combination a valve stem; a casing from which it projects; a handle, having an inner part removably secured to the stem and an outer part, hinged to the extended end of the inner part and adapted to be folded over and locked to the inner part, and when folded, overlying and rendering inaccessible the handle securing means; a hub on said casing, surrounding the said stem, having a shoulder in the path of the handle when moved toward folded position to prevent the handle from rotating the valve when a part thereof is behind the 125 130

shoulder and a part of said handle adapted to bear on the periphery of said hub to prevent said handle parts from being locked together when the said handle part is re-
5 moved from behind the shoulder.

3. A valve lock having in combination a valve stem; a casing from which it projects; a handle, having an inner part removably secured to the stem and an outer part hinged to the extended end of the inner part and adapted to be folded over and locked to the inner part and when folded, overlying and rendering inaccessible the handle secur-
10

ing means; a hub extending around the valve stem and having a notch providing, with 15 the hub, a shoulder, a dog pivoted to the inner part of the handle having a part to drop behind said shoulder when the valve has been placed in a predetermined position by the handle, and having a part to prevent 20 the handle parts from being locked together when the valve is in any other position.

In testimony whereof I hereunto subscribe my name.

LAWRENCE R. JONES.
